UNITED STATES PATENT OFFICE.

MEYER NATHAN MELTZ, OF ATLANTA, GEORGIA.

COUPLING.

Application filed August 23, 1924. Serial No. 733,843.

To all whom it may concern:

Be it known that I, MEYER N. MELTZ, a citizen of the United States, and resident of Atlanta, in the county of Fulton and State 5 of Georgia, have invented certain new and useful Improvements in Couplings, of which the following is a specification.

My invention relates generally to couplings, more particularly to couplings adapted to connect one end of a ribbon to the link 10 which is attached to the stem of a wrist watch or like article, and it consists in the combinations, constructions and arrangements herein described and claimed.

An object of the invention is to provide a coupling of the character described which affords facilities for connecting one end of a wrist band to the link of a wrist watch so that the coupling can be instantly detached 20 from the link without stretching the band or causing any appreciable pressure on the wrist of a wearer but is securely held against accidentally disengaging the link of the wrist watch.

A further object of the invention is the provision of a coupling of the character described which is automatically adjustable to vary the effective length of the coupling 25 within a considerable range.

Other objects and advantages will be apparent from the following description, considered in conjunction with the accompanying drawings, in which—

Figure 1 is a plan view showing the link 30 of a wrist watch connected to one end of a wrist band by the improved coupling.

Figure 2 is a horizontal section through the coupling.

Figure 3 is a longitudinal vertical section 40 through the coupling, and

Figure 4 is a relatively enlarged perspective view of one of the attaching members of the coupling.

The improved coupling comprises a frame 45 which preferably includes a substantially rectangular flat bottom plate 1, a pair of upstanding sides 2 which extend along the longitudinal edges of the bottom 1 from one end of the latter for part of the length there- 50 of and which may be in the form of flanges integral with the bottom plate 1, and a top plate 3 which is coextensive in length with the side members 2. The top plate 3 is secured on the upper edges of the sides 2 and 55 to the bottom plate 1 by a fastening element 4 which is shown as being a rivet extending

through the central portion of the top plate 3 and through the underlying portion of the bottom plate 1. The rivet 4 also has another function which will be hereinafter 60 pointed out.

With the arrangement just described, an end portion of the bottom plate 1 extends beyond the corresponding ends of the sides 2 and the top plate 3 and this extending end 65 portion will be hereinafter referred to as the forward end portion of the bottom plate and is indicated at 5 in Figures 1, 2 and 3.

A transverse partition 6 which extends between the side members of the frame rearwardly of the fastening device 4, divides the space within the frame into a front compartment or pocket 7 and a rear compartment or pocket 8. The front compartment 7 is open at the forward end of the frame 70 while the rear compartment 8 is open at the rearward end of the frame.

The rear compartment 8 is adapted for the reception of an end portion of a ribbon or tape which may be the end portion of a 80 ribbon 9 and which may be permanently secured against displacement from the compartment 8 in any suitable known manner, no means therefor being shown.

A pair of attaching members is provided 85 for cooperating with the frame to connect the latter releasably to the link 10 which is attached in the usual manner to the stem of a wrist watch 11, the other end portion of the wrist band 9 being attached to the wrist 90 watch, as at 12 at a point diametrically opposite to the stem of the watch. These attaching members of the couplings are shown as being hook members 13 and 14 respectively, each of which comprises an elongated flat shank having an upwardly and rearwardly turned bill at its outer end as indicated at 13^a and 14^a respectively and being provided with a vertical eye at its inner end as indicated at 13^b and 14^b re- 95 spectively, through which the rivet 4 extends, whereby the attaching members 13 and 14 will be swingingly supported within the compartment 7. The attaching members 13 and 14 are of sufficient length to extend beyond the front edge of the extended portion 5 of the bottom plate when these attaching elements are engaged at their inner ends with the rivet 4 in the manner just described. It of course will be understood that the fastening element 4 is projected through the eyes of the attaching 105 110

members 13 and 14, at the time the top plate 3 is secured in place on the sides 2 of the frame through the use of the fastening element 4. At this time, the eye portions of the attaching member 14 is placed flatwise upon the bottom plate 1 within the compartment 7 in register with an opening through the bottom plate through which the fastening element 4 will be projected and the eye portion of the attaching member 13 then is placed upon the eye portion of the attaching member 14 so that the eye portion of the attaching member 13 will be superimposed upon the eye portion of the attaching member 14 when the fastening element 4 has been projected through the eyes 13^b and 14^b and has been secured in position to connect the top plate 3 with the bottom plate 1. The outer end portion of the fastening member 13 may be downwardly offset at 13^c so that the outer end portions of the shanks of both the attaching member 13 and the attaching member 14 will lie in the same horizontal plane and in sliding contact with the extending end portion 5 of the bottom plate. It is to be observed at this point that the diameter of the eye 13^b is considerably greater than the diameter of the portion of the rivet 4 that extends therethrough so that the attaching member 13 can have limited longitudinal movement in respect to the frame while still being swingingly supported on the rivet 4.

The shanks of the attaching members 13 and 14 are provided intermediate their length with lugs 13^d and 14^d respectively which are upstanding from the remote lateral edges of the shank portions of the attaching members 13 and 14 and are provided at their upper ends with inwardly turned portions 13^e and 14^e respectively. A substantially U-shaped spreader spring has the arms thereof disposed in a spaced straddling relation to the rivet 4 and has the end portions of such arms outturned as indicated at 16 and engaged with openings in the lugs 13^d and 14^d, whereby the spring 15 tends to swing the attaching members 13 and 14 apart until further swinging movement of these attaching members apart is prevented by the engagement of the end portions of such attaching members with the front end portions of the side flanges of the frame, as illustrated in Figure 2.

From the foregoing description of the various parts of the device, the operation thereof may be readily understood. The bill portions of the attaching members 13 and 14 are conveniently attachable to the link 10 of a wrist watch when the bill portions of such hooks have been swung toward each other against the action of the spring 15 and the frame of the coupling and the link 10 have been moved to such positions in respect to each other that the bill por-

tions of the attaching members will overlie the link 10 and the latter will be engaged by the hooks of the attaching members when such attaching members have been released and have been urged apart at their outer ends by the action of the spring 15. It will be manifest that the spring 15 will function continuously to prevent accidental disengagement of the attaching members 13 and 14 from the link 10 and that these attaching members can be manipulated quickly and easily to permit disengagement of the link 10 of the watch therefrom. It also will be apparent that the combined length of the coupling, the wrist band and the watch will vary according to the straight line distance between the outer end portions of the attaching members 13 and 14 and therefore a wrist band of a given length can be attached to watches of different sizes or worn on wrists of different sizes within a considerable range, the adjustment to compensate for the difference between any two of such sizes being automatic in that the attaching members 13 and 14 will be permitted to move farther apart at their outer ends as the diameter of the watch decreases.

Obviously, my invention is susceptible of embodiment in forms other than that illustrated in the accompanying drawings and I therefore consider as my own all such modifications and adaptations of the form of the device herein described as fairly fall within the scope of the appended claims.

I claim:

1. A coupling of the character described comprising a frame having a bottom plate, a pair of spaced apart side members upstanding from the bottom plate, and a top plate, said bottom plate extending at one end of the frame beyond the side members and beyond the top plate, a combined pivot element and securing device connecting the central portion of the top plate with the underlying portion of the bottom plate, a transverse partition extending between the side members of the frame rearwardly of the combined pivot element and securing device, thus dividing the frame interiorly into a rear compartment and a front compartment, the extending end portion of said bottom plate being at the front of the frame, said rear compartment being adapted for the reception of an end portion of a ribbon or tape, a pair of elongated attaching members having eyes at their inner ends through which said pivot element extends and having hooks at their outer ends, the outer end portions of said attaching members resting upon the extending end portion of the bottom plate in sliding contact therewith, and a spreader spring urging said attaching members apart.

2. A coupling of the character described comprising a frame having a bottom plate, a pair of spaced apart side members up-

standing from the bottom plate, and a top plate, said bottom plate extending at one end of the frame beyond the side members and beyond the top plate, a combined pivot element and securing device connecting the central portion of the top plate with the underlying portion of the bottom plate, a transverse partition extending between the side members of the frame rearwardly of the combined pivot element and securing device, thus dividing the frame interiorly into a rear compartment and a front compartment, the extending end portion of said bottom plate being at the front of the frame, said rear compartment being adapted for the reception of an end portion of a ribbon or tape, a pair of elongated attaching members having eyes at their inner ends through which said pivot element extends and having hooks at their outer ends, the outer end portions of said attaching members resting upon the extended end portion of the bottom plate in sliding contact therewith, and a spreader spring urging said attaching members apart, the eye of the upper of said attaching members being of greater diameter than said pivot element and loosely receiving the latter.

3. A coupling of the character described comprising a frame having a bottom plate, a pair of spaced apart side members standing from the bottom plate, and a top plate, said bottom plate extending at one end of the frame beyond the side members and beyond the top plate, a combined pivot element and securing device connecting the central portion of the top plate with the underlying portion of the bottom plate, a transverse partition extending between the side members of the frame rearwardly of the combined pivot element and securing device, thus dividing the frame interiorly into a rear compartment and a front compartment, the extending end portion of said bottom plate being at the front of the frame, said rear compartment being adapted for the reception of an end portion of a ribbon or tape, a pair of elongated attaching members having eyes at their inner ends through which said pivot element extends and having hooks at their outer ends, the outer end portions of said attaching members resting upon the extended end portion of the bottom plate in sliding contact therewith, and a spreader spring urging said attaching members apart, the eye of the upper of said attaching members being of greater diameter than said pivot element and loosely receiving the latter.

3. A coupling of the character described comprising a frame having a bottom plate, a pair of spaced apart side members standing from the bottom plate, and a top plate, said bottom plate extending at one end of the frame beyond the side members and

beyond the top plate, a combined pivot element and securing device connecting the central portion of the top plate with the underlying portion of the bottom plate, a transverse partition extending between the side members of the frame rearwardly of the combined pivot element and securing device, thus dividing the frame interiorly into a rear compartment and a front compartment, the extending end portion of said bottom plate being at the front of the frame, said rear compartment being adapted for the reception of an end portion of a ribbon or tape, a pair of elongated attaching members having eyes at their inner ends through which said pivot element extends and having hooks at their outer ends, the outer end portions of said attaching members resting upon the extended end portion of the bottom plate in sliding contact therewith, and a spreader spring urging said attaching members apart, the eye of the upper of said attaching members being of greater diameter than said pivot element and loosely receiving the latter.

3. A coupling of the character described comprising a frame having a bottom plate, a pair of spaced apart side members standing from the bottom plate, and a top plate, said bottom plate extending at one end of the frame beyond the side members and

MEYER NATHAN MELTZ.
